UNITED STATES PATENT OFFICE.

THOMAS R. HILL, OF PHILADELPHIA, PENNSYLVANIA, ASSIGNOR TO THE UNITED STATES METALLIC PACKING COMPANY, OF PENNSYLVANIA.

DESIGN FOR AN OIL-CUP.

SPECIFICATION forming part of Design No. 22,385, dated May 2, 1893.

Application filed February 27, 1893. Serial No. 463,974. Term of patent 7 years.

To all whom it may concern:

Be it known that I, THOMAS ROBY HILL, a citizen of the United States, residing at the city and county of Philadelphia, in the State 5 of Pennsylvania, have invented new and useful Improvements in a Design for Oil-Cups, of which the following is a specification.

Reference is to be had to the accompanying drawings which sufficiently illustrate my de-
10 sign, and in which—

Figure 1, is a side elevation of the oil cup or lubricator, and Fig. 2, is a detail plan view of its base portion, in horizontal section on the line x, x , in Fig. 1.

15 The upper lid or cover portion A, of the oil cup presents to the eye opposite vertical parallel side lines or faces a, a , and a convexed top outline a' , merging into an intermediate horizontally ranging flange-like prominence 20 a^2 . The lower portion B, of the oil cup body presents a rounded outline b , surmounted by an upper horizontally ranging bead-like prominence b' , at the visible joint between the two parts A, B. Below the outline b ,

there is a stem or stud presenting outwardly 25 diverging curved side contours $b^2 b^3$, and merging at the top into the rounded outline b , and at the bottom into the bracket or base portion C. The base portion C, of the oil cup projects laterally behind the stud or stem 30 portion located between the lines b^2, b^3 , and as shown at c' , in Fig. 2 of the drawings, and also projects laterally in opposite directions at c^2, c^3 , as shown in Fig. 2, to present horizontally a main rectangular outline into which 35 merges the rounded or semicircular outline or contour c^3 . The circular figures c^4, c^4 , simply represent apertures and are not special features of my design.

What I claim is—

40 The design for an oil cup, substantially as herein shown and described.

In testimony whereof I affix my signature in the presence of two witnesses.

THOMAS R. HILL.
